Primary Examiner — Cynthia Ramirez*Assistant Examiner* — Michael A Maharajh(74) *Attorney, Agent, or Firm* — Greer, Burns & Crain, Ltd.(57) **CLAIM**

The ornamental design for a massager head, as shown and described.

DESCRIPTION

FIG. 1 is a bottom perspective view of a massager head showing our new design;

FIG. 2 is a front view thereof;

FIG. 3 is a rear view thereof;

FIG. 4 is a right side view, the left side being a mirror image thereof;

FIG. 5 is an inverted front view thereof;

FIG. 6 is a top view thereof; and,

FIG. 7 is a bottom thereof.

The broken lines shown in FIG. 6 are for the purpose of illustrating environmental structure, which form no part of the claimed design.
